(57) **CLAIM**

The ornamental design for a body and canister for magnetic filter, as shown and described.

DESCRIPTION

FIG. 1 is a top perspective view of a body and canister for magnetic filter;

FIG. 2 is a left side elevational view of the body and canister for magnetic filter shown in FIG. 1;

FIG. 3 is a right side elevational view thereof;

FIG. 4 is a rear elevational view thereof;

FIG. 5 is a front elevational view thereof;

FIG. 6 is a bottom plan view thereof; and,

FIG. 7 is a top plan view thereof.

The dashed broken lines depict portions of the body and canister for magnetic filter that form no part of the claim.
